UNITED STATES PATENT OFFICE.

ALFRED M. LOCKE, OF MILWAUKEE, WISCONSIN.

COMPACT ATTACHMENT.

Application filed November 9, 1922. Serial No. 599,796.

To all whom it may concern:

Be it known that I, ALFRED M. LOCKE, a citizen of the United States, and resident of Milwaukee, in the county of Milwaukee 5 and State of Wisconsin, have invented certain new and useful Improvements in Compact Attachments; and I do hereby declare that the following is a full, clear, and exact description thereof.

10 This invention relates to vanity cases, and more particularly to what is known as duplex or double cases adapted to contain both rouge and powder cakes.

Heretofore, vanity cases of this general 15 character have been exceedingly bulky in size and awkward to manipulate. According to prior practice they are usually constructed with a central partition forming two separate compartments, one containing 20 the rouge cake and the other the powder cake. Each compartment is provided with a separate puff for the material contained therein and one or both of the compartments are provided with a mirror. Obviously, therefore, it is somewhat difficult 25 to use a case of this type, as the frequent changing from one compartment to the other is necessary and objectionable.

This invention is designed to overcome the 30 above noted defects and to provide a thin, compact vanity case, and to provide a vanity case in which a powder cake and a rouge cake, a mirror and a powder puff may be carried in a single compartment, thereby 35 making the vanity case materially thinner, than has heretofore been possible, and exceedingly cheap to manufacture.

Further objects are to provide a vanity 40 case in which the powder cake and rouge cake may be separately selected or renewed, and to provide a vanity case so organized that a single puff may be employed without danger of the puff becoming loaded with either powder or rouge in a manner which 45 interferes with its effective use.

Further objects are to provide an attachment 50 which may be produced and handled as a unit and which includes a mirror and a rouge cake, the latter removably retained and adapted to be easily replaced; to provide an attachment adapted to be slipped into the top of an ordinary vanity case and to be retained therein without requiring additional securing means; and to provide 55 an attachment which may be simply and

cheaply constructed and which is of ornamental design.

An embodiment of the invention is shown in the accompanying drawings, in which:—

Figure 1 is a view of a vanity case 60 equipped with the attachment and showing the cover in raised position.

Figure 2 is a sectional view through the device.

Figure 3 is a plan view of the pad or puff. 65

Figure 4 is a fragmentary sectional view illustrating a detail of construction.

Figure 5 is a transverse, sectional view through a modified form of rouge cake, and

Figure 6 is a plan view of the plate on 70 which the cake is mounted.

The vanity case chosen for illustration comprises a cylindrical body portion 1 having a rather shallow top 2 joined thereto by means of a hinge 3, such hinge being 75 conveniently retained in position by means of ears 4 (see Figure 1) passing through the walls of the top and body portion and clinched in position. If desired, a fastener of any desired type, not shown, may be 80 used to retain the top in closed position.

Within the body portion a powder cake 5 is removably secured, as by means of a few drops of adhesive paste upon its bottom surface. Above the bottom cake a puff is positioned, such puff having a body portion of wool or velour, as indicated at 6. The upper portion of the puff has a satin chamois skin cover 7 which has a circular aperture 8 85 therein located eccentrically. If desired, a suitable edging or binding may be employed. 90

The attachment comprises a stamping 9, which is generally circular in contour and has a depressed portion within which a cup-shaped recess 10 is formed, such recess preferably having a raised, slightly rounded edge 11 to give a finished appearance. A laterally projecting indentation 12 communicates with the recess, as is shown in detail in Figure 4, and facilitates removal of the cake 95 by permitting the insertion of a pointed tool or object. The recess 10 is adapted to accommodate a rouge cake 13 which is removably seated therein and retained in position temporally by means of adhesive paste upon its bottom surface, or, in any desired manner. This circular member 9 is provided with a somewhat crescent shaped cutout 14, beneath which cutout a mirror 15 is positioned. The mirror may be provided 100 105 110

with diagonal or slanting edges 16 which provide a reentrant angle which accommodates the cup-shaped recessed or depressed portion, as may be seen from Figure 1.

It is found that the glass may be cut with greater facility along the slanting straight edges 16 than would be possible if the glass had to be cut along a curved edge.

The stamping 9 is provided with a plurality of lugs 17 which are inturned beneath the mirror 15, as may be seen from Figures 1 and 2, to hold the mirror in position. The bottom edge of the stamping 9 may be provided with cutouts 18 to accommodate the ears 4 of the hinge. This entire unit is adapted to be formed, handled, and sold, as a separate entity and is adapted to be slipped into place within a vanity case and to be retained in position by the frictional engagement between the walls of the parts, as for instance, the walls of the top and the margins of the stamping.

In some instances it may be desired to eliminate the indentation 12, due to the fact that the same mars the finish and appearance of the plate 9. In such instances, I propose to provide for the removal of the cake 13 from the cup-shaped recess by the provision of a lip 13' punched out of the plate 13'' on which plate the rouge cake is mounted. As best shown in Figure 5, the lip 13' is normally covered by the cake, until such time as the latter is worn down by use, thereby exposing the lip 13' which permits the insertion of a button-hook, or other suitable object, thus enabling the remaining portion of the cake to be easily removed.

It is to be particularly noted that by the construction shown, it is possible for one manufacturer to produce these units, including the mirror and a rouge cake receptacle, and to furnish manufacturers of vanity cases, or dealers therein, with these units, which may be instantly positioned within the top of the casing, as illustrated in the drawings.

It is also to be noted that the ears 17 may be dispensed with, under certain conditions, as when the complete vanity case is produced by a single manufacturer. Also the cup for the rouge may be formed independently of the main member 9.

It is further to be noted that by the peculiar arrangement of the puff, the rouge cake 13 contacts only with the exposed portion 19 of the soft or fleecy portion of the puff, while the chamois skin covering 7 provides a clean portion adapted to be gripped by the user's fingers, thereby avoiding soiling of the fingers.

It will be seen, therefore, that an extremely serviceable vanity case and attachment therefor has been produced and that such device functions in a novel and efficacious manner.

Attention is also directed to the fact that while the present invention permits of a very compact structure, it also allows the use of comparatively larger rouge and powder cakes, due to the fact that the entire compartment may be utilized with the exception of a small space taken up by the puff, which, in practice, can be made very thin.

Although the invention has been described in considerable detail, it is to be understood that it may be variously modified and it is, therefore, to be limited only as set forth in the appended claims.

I claim:

1. A vanity case comprising a body portion having a powder cake therein, a top hingedly joined to said body portion and having a flanged edge, a stamping spaced from the top portion of said top and having a cutout and a depressed portion, a rouge cake carried within said depressed portion, a mirror located behind said cutout, and a puff adapted to be positioned upon said cake, said puff having a fibrous body portion and a chamois skin top provided with a cutout adapted to register with the cake of rouge.

2. A vanity case comprising a casing having a bottom portion and a flange top portion hinged thereto, a plate mounted in said top portion and having a cutout, a mirror located between said plate and the upper portion of said top and displayed through said cutout, and a cup carried by said plate and adapted to receive a rouge cake, said mirror having its outer margin contoured to and bearing against the flange of said top and its inner margin abutting the wall of said cup.

3. An attachment for a vanity case comprising a stamping having a peripheral portion adapted to frictionally engage the inner surface of the walls of the vanity case and having a cutout portion, a depressed, cup-shaped member integrally formed with the stamping and adapted to accommodate a rouge cake, and a mirror positioned behind said cutout portion.

4. A vanity case comprising a casing having a bottom portion and a flanged top portion hinged thereto, a plate mounted in said top portion and having a cutout and a depressed cup portion spacing said plate from the top portion of said top, a mirror located between the flange of said top and the depressed cup portion and positioned in the space between said plate and the top portion of said top, whereby a rouge cake may be carried in said cup, and whereby said mirror is displayed through said cutout portion.

5. A vanity case comprising a circular casing having a bottom portion adapted to receive a powder cake and having a flanged, hingedly-joined circular top portion, a stamping positioned within said top portion,

and having a depressed cup shaped portion integrally formed therein and spacing said stamping from the top of said top portion, and having a crescent shaped cut-out corresponding roughly to the circular contour of said top, and to the contour of said cup shaped portion; and a mirror located behind said stamping adjacent said cut-out and visible therethrough.

19 6. A vanity case comprising a circular bottom portion and a hingedly-joined circular and flanged top portion cooperating therewith, a circular plate positioned within said top portion and having a depressed

cup shaped portion spacing said plate from the top of said top portion, and having a crescent shaped cut-out and a mirror positioned between said plate and said top, and having a marginal portion contacting with the flange of said top, and a second marginal portion contacting with the wall of said depressed cup portion.

In testimony that I claim the foregoing I have hereunto set my hand at Milwaukee, in the county of Milwaukee and State of Wisconsin.

ALFRED M. LOCKE.
